(57) **CLAIM**

The ornamental design for an “archery bow sling and cover,” as shown and described.

DESCRIPTION

FIG. 1 is a perspective view of an archery bow sling and cover showing my new design;

FIG. 2 is a front elevation view thereof;

FIG. 3 is another perspective view thereof;

FIG. 4 is a top perspective view thereof;

FIG. 5 is a left side elevation view thereof; and,

FIG. 6 is a right side elevation view thereof.

The dashed lines shown on the surface of the bow cover are understood to represent stitching.

The phantom lines are for illustrative purposes only, and form no part of the claimed design.
